US00D427525S

United States Patent [19]

Hayes et al.

[11] Patent Number: Des. 427,525

[45] Date of Patent: ** Jul. 4, 2000

[54] FOOD CONTAINER

[75] Inventors: **Thomas J. Hayes; Mark A. Erickson**, both of McHenry, Ill.; **Raj K. Mangla**, Pittsford, N.Y.; **Mark Spencer**, Gurnee, Ill.; **Michael J. A. Sagan**, Marshall, Wis.

[73] Assignee: **Tenneco Packaging, Inc.**, Lake Forest, Ill.

[**] Term: **14 Years**

[21] Appl. No.: **29/090,541**

[22] Filed: **Jul. 10, 1998**

[51] LOC (7) Cl. **09-03**

[52] U.S. Cl. **D9/431**

[58] Field of Search D9/337-338, 341, D9/345, 424-425, 432, 347, 445; D7/553.1, 553.6, 553.7, 553.8, 629; 206/564, 541; 220/555, 575; 446/114, 115

CLAIM

The ornamental design for a food container, as shown and described.

DESCRIPTION

FIG. 1 is a top perspective view of a food container showing our new design;

FIG. 2 is a top view;

FIG. 3 is a front view;

FIG. 4 is a left side view; the right side view being a mirror image thereof; and,

FIG. 5 is a rear view.

The bottom of the food container forms no part of the claimed design.
